UNITED STATES PATENT OFFICE.

FREDERICK TICHY, OF ASTORIA, AND FREDERICK H. WAPPLER, OF ELMHURST, NEW YORK, ASSIGNEES TO WAPPLER ELECTRIC COMPANY, INC., OF LONG ISLAND CITY, NEW YORK, A CORPORATION OF NEW YORK.

COMBINED TOOL BOX AND STEP FOR MOTOR VEHICLES.

Application filed September 8, 1922. Serial No. 586,830.

To all whom it may concern:

Be it known that we, FREDERICK TICHY and FREDERICK H. WAPPLER, both citizens of the United States, the former residing in 5 Astoria, in the county of Queens and State of New York, and the latter residing in Elmhurst, in the county of Queens and State of New York, have invented certain new and useful Improvements in Combined Tool 10 Boxes and Steps for Motor Vehicles, of which the following is a full, clear, and concise description:

Our invention relates to combined tool boxes and steps for motor vehicles.

15 More particularly stated our invention comprehends a construction whereby a tool box and a swinging step are mounted adjacent the running board or analogous portion of a motor vehicle, in such manner that 20 the vehicle step is automatically moved into position for active use whenever the door of the vehicle is opened, and is moved into a position of inactivity and thus practically caused to disappear whenever the door of 25 the vehicle is closed, the tool box being closely associated with the step, and being automatically rendered accessible when the step is in position for active use, but inaccessible when the step is in its position of 30 activity.

Our invention further comprehends various improvements in connection with the step and tool box, and with various parts more or less remotely associated therewith.

35 Reference is made to the accompanying drawing forming a part of this specification, and in which like reference characters indicate like parts throughout the several figures.

40 Figure 1 is a fragmentary section through a motor vehicle provided with our invention, the step being shown in full lines in its position of active use and in broken lines in its position of inactivity, the section being 45 taken on the line 1—1 of Figure 3, looking in the direction indicated by the arrows.

Figure 2 is a section on the line 2—2 of Figure 3, looking in the direction indicated by the arrows.

50 Figure 3 is a fragmentary side elevation showing the mechanism of Figure 1 as the same would be seen in said figure by a person standing at the right thereof.

Figure 4 is a fragmentary section on the

line 4—4 of Figure 3, and shows the tool 55 box as drawn out over the step.

The body of the vehicle is shown fragmentarily at 5, and is provided with a floor 6, a doorway 7 and a door 8, the door being connected with the vehicle body by 60 means of hinges, one of which appears at 9.

Connected with the vehicle body and extending downwardly therefrom is a side plate 20, made preferably of sheet metal. The vehicle is further provided with an 65 underframe 11, disposed adjacent the side plate 10. A pair of metallic supporting arms 12, each of substantially L-shape as shown in Figure 2, are used to support the running board shown at 13. The supporting 70 arms 12 are held in position by means of bolts 14, and the running board is mounted upon the supporting arms by bolts, one of which is shown at 15 in Figure 2. Thus the running board is secured rigidly in position. 75 A pair of stirrups 16 are by means of bolts 17 secured firmly upon the underside of the running board 13, so as to depend therefrom. These stirrups are parallel with each other, as may be understood from Figure 2. 80 Extending through these stirrups and partially supported thereby are a pair of end blocks 18. These end blocks are made in this instance of wood, and are disposed parallel to each other and located upon the 85 under side of the running board 13.

Engaging the lowermost edge portion of each of the two end blocks 18 are a pair of brace beams 19 and 20, each having the form of a rather thick and narrow board. 90 Bolts 21 extend downwardly through the running board 13 and through the end blocks 18 and brace beams 19. Nuts 22 are mounted upon the lower ends of the bolts 21, and are tightened sufficiently to clamp firmly together the various parts through which the bolts 21 extend.

A pair of hinge bars 23 and 24 are mounted rigidly upon the end blocks 18, and extend obliquely downward and outward, as 100 may be understood from Figures 1 and 2. A step 25, having in this instance the form of a flat board, is supported upon the hinge bars 23 and 24 by means of a pair of hinge pins 26 and 27, so that the step can swing 105 relatively to the end blocks.

Located adjacent the hinge bars 23 and 24 are a pair of supporting bars 28 and 29.

These supporting bars are by means of pins 30 and 31 pivotally connected to the opposite ends of the step 25. A pair of guide blocks 32 and 33 are mounted rigidly upon the end blocks 18 and each provided with a hole 34, one of the holes being shown at 34 in Figure 2. The two supporting bars 28 and 29, one at each end of the steps 35, extend slidably through the holes in the two guide blocks 32 and 33. The supporting bars 28 and 29 are slightly curved adjacent their outer or lower ends, as may be understood from Figures 1 and 2. By this arrangement, whenever the step 29 is in the position indicated for it by full lines in these two figures, the inner or upper portions of the supporting bars 28 and 29 rest edgewise against the adjacent hinge bars 23 and 24, so that the supporting bars 28 and 29 are effectively braced by the hinge bars and thus support the step 25 so that the latter is capable of sustaining considerable weight. When, however, the step 25 is swung upwardly, so as to occupy the position indicated for it by broken lines in Figures 1 and 2, the supporting bars 28 and 29 are lifted out of engagement with the hinge bars 23 and 24, and are thrust some little distance through the guide blocks 32 and 33, as indicated by broken lines in the two figures just mentioned.

Mounted upon one end of the step 25 is a sector 35, held in position by the pins 31 and 27 above mentioned, so that the sector 35 and the step are thus connected together, and move as a unit. The sector 35 carries a pin 36, and the latter extends through an actuating bar 37. This actuating bar is by means of a pivot pin 37^a connected with the lower end of a pitman 38. The pitman is mounted to rock upon a pin 39, and is provided with a slot 40. The pin 39 is carried by a supporting arm 41, having a substantially L-shape as may be understood from Figure 1, and is held in position upon the adjacent end block 18 by means of bolts 42.

Above the pitman 38 is another pitman 43, carrying a pin 44 which extends through the slot 40 of the pitman 48. The pitman 43 is mounted to rock upon a pin 45, this pin being carried by a hanger 46 the hanger being secured upon the underside of the floor 6 by means of bolts 47.

A tensile spring 48 is connected with the pitman 43, and a push rod 49 is also connected with the pitman. The spring 48 is connected with a standard 50 which is mounted rigidly upon the frame work, and the push rod 49 extends slidably through a hole in the standard 50. In consequence of the tension of the spring 48 the push rod has a tendency to move toward the right so as to occupy the position indicated for it by full lines in Figure 1. It therefore main-

tains this position except when moved from it as described below.

The vehicle door 8 carries a push plate 51, shown more particularly in Figure 2. This push plate is so located and arranged that whenever the door 8 is closed the push plate 51 is brought into engagement with the adjacent end portion of the push rod 49; and thus by the closure of the door the push rod 49 is moved endwise, from the position indicated for it by full lines in Figure 1 to the position indicated for it by broken lines in said figure.

The movement of the push rod 49 just described increases the tension of the spring 48, and causes the pitman 43 to rock in a counter-clockwise direction according to Figure 1. This rocking movement of the pitman 43 causes the pitman 48 to rock in a clockwise direction according to the figure just mentioned. This rocking movement of the pitman 48 causes the sector 35 to rock in a counter-clockwise direction according to this figure, and this causes the step 35 to swing upwardly, from the position indicated for it in full lines to the one indicated for it by dotted lines in the said figure.

The step 25 remains in the position indicated for it by broken lines in Figure 1, so long as the door 8 remains closed. When, however, the door is opened the tension of the spring 48 causes the various movable parts above described each to rock or otherwise move in a direction contrary to that in which it moves in consequence of the closing of the door. Thus whenever the door 8 is swung open, the step 25 swings downwardly into the position indicated for it by full lines in Figures 1 and 2 and above described at length.

The tool box is shown at 52, and has generally the form of a chest. It is provided with a cover 53 and with a lock 54. The tool box is mounted upon a pair of sliding rails 55, to which it is firmly secured by means of bolts 56, as shown more particularly in Figure 4. The sliding rails 55 extend into a pair of slots 57 with which the end blocks 18 are provided. Thus the sliding rails 55, carrying the tool box 52, are supported by the end blocks 18.

The tool box is operated altogether by hand. It is inaccessible so long as the step 25 remains raised into the position indicated for it by broken lines in Figures 1 and 2, or in other words so long as the vehicle door remains closed. When, however, the step is lowered or swung downwardly into the position indicated for it by full lines in Figures 1 and 2, the tool box is thereby rendered accessible.

The operator, in order to open the tool box, simply grasps it by hand and draws it out like a bureau drawer so that it protrudes beyond the outer edge of the running

board 13, to any extent desired by the operator. This done, the operator unlocks the cover and swings it upwardly or removes it, so as to leave the tool box open. When the operator is through using the tool box he closes and locks it, and then pushes it back under the running board 13, far enough to be out of the way of the step 25, so as to give the latter room to swing upwardly.

10 As may be understood from the foregoing description neither the operator or any other person can open the tool box unless the door of the vehicle is open. Such being the case, no unauthorized person can remove any article from the tool box, or tinker with its contents, except when the vehicle door is open; and in such event the owner or other occupant of the vehicle is likely to know what is going on.

20 Even independently of the tool box, however, the step 25, actuated and controlled in the manner above described, possesses some distinct advantages. Whenever the motor vehicle stops and the door is opened, the 25 step 25, normally out of the way and hidden, swings downwardly and into position for use as a vehicle step, its action being to all intents and purposes automatic. When the motor vehicle is in condition to proceed 30 upon its journey and the door is accordingly closed, the step is raised and thus disappears, this action also being practically automatic.

We do not limit ourselves to the precise 35 mechanism shown, as variations may be made therein without departing from our invention, the scope of which is commensurate with our claims.

Having thus described our invention, what 40 we claim as new and desire to secure by Letters Patent is as follows:

1. In a device of the character described 45 the combination, with a vehicle body provided with a running board and with a door so mounted as to permit of being opened and closed, of supporting members carried by said vehicle body and located underneath the running board, a tool box mounted upon said supporting members and located below 50 said running board, a step supported by said running board and disposed adjacent said tool box, said step being mounted to move and having two normal positions, in one of which the step serves as a barrier to prevent access to the tool box, and connections from said step to said door for enabling movements of the door to shift the step from one of said normal positions to the other.

60 2. In a device of the character described the combination, with a running board, of a tool box located beneath said running board, and a step mounted below said running board and below said tool box, said step being movable into two normal posi-

tions, one for use as a vehicle step and the other for use as a barrier to prevent access to the tool box.

3. In a device of the character described the combination, with a running board, of 70 a pair of end blocks mounted upon the underside of said running board and depending therefrom, said end blocks being provided with slots, a pair of rails extending into said slots and slidably relatively to said end blocks, a tool box secured to said rails and movable therewith as a unit, so that said tool box and said rails may be moved outwardly after the manner of a drawer, a step journaled upon said end blocks and 75 mounted to swing into two normal positions in one of which it serves as a vehicle step and in the other as a barrier to prevent access to the tool box, and mechanism connected with said step and controllable by the operator for shifting said step from one to the other of the two normal positions.

4. In a device of the character described the combination of a tool box, a swinging member disposed adjacent said tool box and 80 having a normal position as a step and another normal position as a barrier for preventing access to the tool box, and mechanism connected with said swinging member and controllable by the operator for the purpose of shifting said swinging member from one to the other of its said normal positions.

5. In a device of the character described the combination, with a vehicle body provided with a running board and with a 100 swinging door, of a pair of end blocks mounted on the underside of said running board, a tool box slidably mounted upon said end blocks and movable by hand after the manner of a drawer for the purpose of facilitating access to the contents of the tool box, a swinging member having the form of a flat board and mounted adjacent said tool box, said swinging member having a normal position in which it acts as a barrier 105 to prevent access to the tool box, and connections from said swinging member to said swinging door, for the purpose of enabling the closing movement of the door to shift said swinging member from one of its normal positions to the other.

6. In a device of the character described the combination, with a vehicle body having a running board and a swinging door, of a 110 pair of end blocks mounted upon the underside of said running board and spaced apart, a tool box slidably mounted upon said end blocks and thereby supported so as to enable the tool box to be slid back and forth relatively to the running board, a swinging member journaled upon said end blocks and having two normal positions one to enable the swinging member to act as a vehicle step and the other to enable it to act as a barrier for preventing access to the tool box,

and actuating mechanism carried by the vehicle body and connected with said swinging member for the purpose of shifting the swinging member from one to the other of its two normal positions, said actuating mechanism being connected with and controllable by the opening and closing movements of the door.

7. In a device of the character described 10 the combination, with a vehicle body having a running board and a swinging door so mounted as to permit of it being opened and closed, of a pair of supporting members located beneath the running board, a tool box 15 mounted upon said supporting members, a step carried by the vehicle body and disposed adjacent said tool box, said step being mounted to swing and having two normal positions, said step serving in one of its 20 positions as a barrier to prevent access to the tool box, actuating mechanism carried by the vehicle body and connected with said step for shifting the same from one of its normal positions to the other, and means

for enabling the opening and closing movements of the door to control actuating mechanism. 25

8. In a device of the character described the combination, with a vehicle body having a running board and provided with a door 30 mounted to open and close, of a pair of end blocks located underneath the running board, a tool box mounted upon said end blocks, a step supported adjacent said tool box, said step being movable into two normal 35 positions, in one of which it acts as a vehicle step and in the other of which it acts as a barrier to prevent access to the tool box, an actuating bar connected with said step for shifting the same from either of its normal positions into the other, and mechanism connected with said actuating bar and controllable by movements of the door for shifting said step from one of its said normal positions to the other. 40

FREDERICK TICHY.
FREDERICK H. WAPPLER.
